Primary Examiner — Sharon S Oum*(74) Attorney, Agent, or Firm* — McGarry Bair PC(57) **CLAIM**

The ornamental design for a ceiling fan motor housing, as shown and described.

DESCRIPTION

FIG. 1 is a top perspective view of a ceiling fan motor housing, showing my new design;

FIG. 2 is a top view thereof;

FIG. 3 is a bottom view thereof;

FIG. 4 is a right side view thereof;

FIG. 5 is a rear view thereof;

FIG. 6 is a front view thereof; and,

FIG. 7 is a left side view thereof.

Portions of the ceiling fan motor housing and ceiling fan environment shown in broken lines form no part of the claimed design.

1 Claim, 7 Drawing Sheets(56)
